CASING FOR LOUDSPEAKER DRIVER UNIT AND ITS TRANSFORMER

Sidney E. Levy, White Plains, and Maurice M. Condon, Pleasantville, N. Y., assignors to University Loudspeakers, Inc., White Plains, N. Y., a corporation of New York

Application April 1, 1950, Serial No. 8,902

Term of patent 14 years

(Cl. D26—15)

To all whom it may concern:

Be it known that we, Sidney E. Levy and Maurice M. Condon, both citizens of the United States of America and residents, respectively, of White Plains, New York, and Pleasantville, New York, have invented a new, original, and ornamental Design for a Casing for Loudspeaker Driver Unit and Its Transformer, of which the following is a specification, reference being had to the accompanying drawings, forming part thereof.

Fig. 1 is a side view, partly in perspective, of our casing,

Fig. 2 is a bottom view of our casing, and

Fig. 3 is a top view of our casing.

We claim:

The ornamental design for a casing for loudspeaker driver unit and its transformer, substantially as shown.
